UNITED STATES PATENT OFFICE.

JOHN HENRY THEBERATH, OF NEWARK, NEW JERSEY.

DESIGN FOR A SCARF-PIN.

SPECIFICATION forming part of Design No. 23,534, dated August 7, 1891.

Application filed July 11, 1894. Serial No. 517,256. Term of patent 3½ years.

To all whom it may concern:

Be it known that I, JOHN HENRY THEBERATH, of Newark, in the county of Essex and State of New Jersey, have invented a new and original Design for a Pin, of which the following is a full, clear, and exact description.

Reference is to be had to the accompanying drawing in which the figure represents a front view of a pin embodying my new design.

The leading feature of my design consists in the grotesque figure shown in the drawing.

I claim—

The design for a pin herein shown and described.

JOHN HENRY THEBERATH.
